ATT'Y.

UNITED STATES PATENT OFFICE.

GEORGE F. BUTTERFIELD, OF STONEHAM, MASSACHUSETTS.

SHOE-SOLE VULCANIZING AND APPLYING APPARATUS.

SPECIFICATION forming part of Letters Patent No. 627,840, dated June 27, 1899.

Application filed October 5, 1898, Serial No. 692,703. (No model.)

To all whom it may concern:

Be it known that I, GEORGE F. BUTTERFIELD, of Stoneham, in the county of Middlesex and State of Massachusetts, have invented 5 certain new and useful Improvements in Shoe-Sole Vulcanizing and Applying Apparatus, of which the following is a specification.

The object of this invention is to provide improved apparatus for applying vulcanizable-rubber soles and heels to the bottoms of 10 leather boots and shoes, so as to secure thereon by heat and pressure a yielding and water-proof tread-surface without injury to the leather in the process of applying and vulcanizing the rubber.

My present invention is in the nature of improvement upon devices heretofore patented by me for this purpose under date of September 28, 1886, No. 349,690, December 29, 1896, 20 No. 574,238, and January 4, 1898, No. 596,476, my aim being to hold the leather shoe firmly while the rubber sole is being secured to its bottom by vulcanization, and yet keep the upper-leather sufficiently cool to be uninjured.

One feature of my present improvement 25 consists of a closed steam-chamber and a movable mold-plate placed thereon about as shown in the drawing illustrating my method of vulcanizing rubber soles to leather shoes patented December 29, 1896, No. 574,239.

Other features of improvement include 30 novel shoe-holding devices and novel means for pressing the lasted shoe upon the rubber in the mold, stops for limiting the movement properly, and means for lowering and raising 35 the shoe and holder by use of an elastic fluid, (preferably compressed air;) also, suitable swinging adjustable marginal plates or clamps for securing the marginal plates in 40 position with cold-air passages at the bearing edges; also, an annular inflatable bag or cushion surrounding the last or shoe-holder and between the shoe and its last, said cushion being inflated after insertion to retain or provide 45 for the passage of a current of cold air or water within the shoe-body; also, the shoe-holder last detachable from and pivoted upon the foot of the vertically-moving shaft and provided with adjusting-screws to raise or 50 depress the toe portion at will.

In the drawings, Figure 1 is a side elevation, partly in section, of one of my machines. Fig.

2 is a transverse section on line 2 2 of Fig. 1. Fig. 3 is a vertical section of one form of my shoe-holder.

55

A represents a suitable frame or hollow standard provided at its upper end with a recessed head A', adapted to receive and support the cylindrical chamber B, having the inclosed piston C, actuated by hydraulic pressure or 60 by steam or compressed air. The cylinder B is laterally adjustable to locate it properly and is firmly fixed for use. Flexible or other pipes D convey the elastic fluid, and a four-way cock or equivalent device admits it at one 65 side of the piston and discharges it from the other side as required. A suitable stop is provided to limit the downward stroke, such stop being shown in Fig. 1 as a yoke E, engaging a collar E', formed on or secured to the shaft 70 or piston-rod F, protruding through the lower end of the recessed head A' and cylinder B. The overhanging frame supporting the cylinder and other parts gives the workmen unobstructed access to the vulcanizer.

75

Directly beneath the cylinder B is the steam-chamber G; with suitable inlet and outlet pipes preferably entering from below and furnished with stop-cocks to control the steam-current. Other like pipes admit and discharge a water-current when it is desired to cool the chamber. The top of the chamber G is flat or of other shape to conform to the bottom of the mold-plate, and upon such top is held the mold-plate H, having in its upper 80 surface the sole-shaped or sole and heel shaped mold h to receive the rubber compound to be vulcanized to the shoe-bottom, as in my three patents first herein referred to, or the vulcanized sole to be secured to the 85 shoe-bottom by curing the interposed vulcanizable sole-layer thereon, as in my process Patent No. 574,239. The mold-plate H is adjustable to proper position beneath the piston-rod and when adjusted is held fast by bolts 90 or clamps, so that it will remain in place when the shoe and its rubber sole are to be raised therefrom.

The lower end of the piston-rod F carries 100 a last or shoe-holder J, upon which the shoe under treatment is mounted. This holder may be an ordinary last, but is preferably a hollow metallic last having flexible pipes communicating with its interior and connected

with a cold-water supply to keep the last cool and the shoe-upper from being overheated, as provided in my Patent No. 596,476.

In Fig. 3 the last is shown pivoted by a transverse pin K to ears at the foot of the piston-rod. Adjusting-screws k, threaded through a lateral projection on the foot of the shaft or rod F, bear on the top of the last to elevate or depress the toe portion thereof, and thus to adjust the shoe-holder upon the axis K.

L L represent swinging marginal plates or clamps to hold down the marginal plates, which, as shown in my two patents of December 29, 1896, fit in laterally at the inseam of the shoe and hold down the shoe by its sole edges upon the rubber in the mold h, preventing the rubber from escaping upwardly when expanded in vulcanizing. Under my present improvement the parts L L, with their connections, may serve to hold the former marginal plates securely down, serving thus as clamps only, or they may, as herein shown, be substituted for said marginal plates and the screws and skeleton frame by which such plates were held down. In this latter case the edges of the parts L will be shaped accurately to the contour of the shoe, each conforming to one side of it, and in either case said parts will be provided with suitable adjusting devices for moving them into and holding them in position at the side of the shoe and for drawing them down and securely holding the shoe and resisting the expansion of the rubber. The adjusting devices shown include side plates M, which may be set as required by screws m or otherwise to bear against the tapering sides of the clamps L, and also a powerful screw S, threaded through a cross-bar a of the frame and engaging a connecting-piece P, Fig. 2, at the lower part of the clamps to draw them downwardly. A cold-air passage L' is formed through these clamps at their extremities, to which compressed air is supplied through a suitable pipe L² and numerous small perforations l to deliver this air against the upper leather in jets, cooled as it expands in escaping, so as to keep the leather from injury by heat and lower the temperature in the shop.

In Fig. 3 the shoe-holder is shown reduced in size to admit between it and the leather upper of the shoe an inflatable rubber bag N of irregular annular form, tapering upwardly and having externally about the shape of the interior walls of the shoe. These walls are distended by the air-pressure, so that the leather and lining are kept cool, free from wrinkles, and from contact with the last. This bag will be in a collapsed state when introduced into the shoe with the last and will be subsequently inflated and the air confined therein by the stop-cock n.

I claim as my invention—

1. In a shoe-sole vulcanizing and applying apparatus, the closed steam-chamber G and the independent mold-plate H h adjustable

and adapted to be secured thereon, in combination with a suitable frame and means for pressing the leather shoe upon the rubber contained in the mold formed in said mold-plate, substantially as set forth. 70

2. In a shoe-sole vulcanizing and applying apparatus, the steam-chamber, the adjustable, independent mold-plate thereon and suitable means applied within the shoe for pressing and firmly holding the shoe upon the rubber contained in the mold during vulcanization, in combination with swinging, marginal clamps adapted to apply downward pressure upon the upper surface of the sole edge and welt to resist the escape of rubber from the mold along such edge, substantially as set forth. 75

3. In a shoe-sole vulcanizing and applying apparatus, the steam-chamber, the mold-plate thereon, and means applied within the shoe for pressing it upon the rubber contained in the mold during vulcanization, in combination with swinging, lateral clamps fitting marginally along the inseam of the shoe and bearing downwardly upon the sole edge and welt and with suitable pressure devices, substantially as set forth. 80

4. In a shoe-sole vulcanizing and applying apparatus, the steam-chamber, the mold-plate thereon and suitable shoe-holding devices, in combination with swinging marginal clamps pivoted and actuated at a point below the steam-chamber and with lateral adjusting devices, substantially as set forth. 95

5. In a shoe-sole vulcanizing and applying apparatus, the frame having a chambered head, a piston therein with protruding piston-rod, and pipes for conveying the elastic fluid to and from said chamber, in combination with the steam-chamber and mold-plate thereon, and with shoe-holding devices connected to the piston-rod adapted to present the shoe over and upon the rubber contained in the mold, and thereby to firmly affix the rubber sole to the leather shoe-bottom, substantially as set forth. 105

6. In a shoe-sole vulcanizing and applying apparatus, the frame having a recessed head, an adjustable chamber in said head and a piston in said chamber with downwardly-protruding piston-rod, in combination with the steam-chamber and mold-plate thereon, located beneath said piston, a shoe-holding device connected to the piston-rod and an adjustable stop limiting the downward movement of the piston, substantially as set forth. 115

7. In a shoe-sole vulcanizing and applying apparatus, the shoe-holder J, connected to the foot of the plunger by a transverse pivot K and provided with adjusting-screws adapted to elevate or depress the toe portion of the shoe upon said pivot, as required, substantially as set forth. 125

8. In a shoe-sole vulcanizing and applying apparatus, a shoe-holder connected to the shaft of the pressure device and consisting of a rigid body having a sole-shaped bottom serv- 130

ing to press the shoe-sole upon the rubber in the mold, in combination with an inflatable upwardly-tapering annular bag surrounding said body, between it and the upper-leather 5 of the shoe, and adapted to hold such upper-leather distended, cooled and free from contact with the mold and with said body, substantially as set forth.

9. In a shoe-sole vulcanizing and applying 10 apparatus, the steam-chamber and mold-plate and means for pressing the leather shoe-bottom upon the rubber in the mold, in combination with marginal plates held firmly down

upon the sole edge and welt and formed with an air-passage and with perforations for air-jets therefrom against the leather along the bearing edges of said plates, such passages being supplied with air under pressure, substantially as set forth.

15 In testimony whereof I have affixed my signature in presence of two witnesses.

GEORGE F. BUTTERFIELD.
